UNITED STATES PATENT OFFICE.

JOHN B. CHRISTIAN AND WILLIAM D. HANSON, OF HAMBURG, IOWA.

TONGUELESS CULTIVATOR.

SPECIFICATION forming part of Letters Patent No. 292,283, dated January 22, 1884.

Application filed August 16, 1883. (No model.)

To all whom it may concern:

Be it known that we, JOHN B. CHRISTIAN and WILLIAM D. HANSON, citizens of the United States, residing at Hamburg, in the 5 county of Fremont and State of Iowa, have invented certain new and useful Improvements in Tongueless Cultivators, of which the following is a specification, reference being had therein to the accompanying drawings.

10 This invention relates to certain improvements in tongueless cultivators and like machines; and it has for its object to improve the efficiency of the transportation of these machines either in the field or on the road.

15 Our improvement consists in novel means for connecting the shoe or runner directly to the hitch-supports of the frame-work of the cultivator.

Our improvement further consists, in the 20 combination with each gang of plows, of a pivoted iron shoe or runner for supporting the gang of plows from the soil while being moved from the field or upon the road.

Our improvement further consists in the 25 novel construction and arrangement of parts, as will be hereinafter more fully set forth, and pointed out in the claims.

In the annexed drawings, Figure 1 is a perspective view of a tongueless cultivator with 30 our improvements applied thereto, and Fig. 2 is a side view of the same.

In the figures, A represents an axle of the elevated class, provided with the horizontal end portions, *a*, for the attachment of the 35 plow-beams B through the agency of the couplings C, which have an axial bearing thereon. The plow-beams are pivotally connected to the coupling C by means of pins *b* or otherwise, to secure the compound motion—vertically and laterally—to the plow-beams. The 40 couplings C are provided at their inner forward ends with stops *c*, to arrest the downward movement of the beams carrying the gang-plows by coming in contact with the 45 vertical arms of the arched axle, substantially as seen in Figs. 1 and 2 of the drawings. Upon the outer end of the horizontal portions of the axle are placed the sleeves D, suitably secured thereto by coupling-rivets or otherwise. To the forward portion of each sleeve

D is suitably attached a horizontal arm, *d*, to which is pivotally connected the shoe or runner E by means of the parallel overhanging arm *e* and pin *f*, or its equivalents, passed through the perforation in the arm and the 55 perforation in the upper end of the shoe. These shoes are made curved, almost S-shaped, and the lower ends are turned rearwardly to secure the proper support for runners on the soil. To the upper forward ends 60 of the shoes the whiffletree attachments are made. To the outer side of each plow-beam is secured a plate or bracket, *h*, to which is pivoted a curved iron shoe, F, having its fulcrum at *i*. Also, in rear of each bracket *h* is 65 pivoted a bar, *k*, formed at its lower end with an eye or catch to receive the upper end of the curved shoe F when raised, and retains the same in the elevated position while the cultivator is at work in the field.

70 When it is desired to move the cultivator from one field to another, or to transport the same over a road, the catches are released from the upper end of the curved shoes F, and in so doing the shoes drop by gravity into the 75 position indicated by Fig. 2, the lower end striking the soil and raising the plows therefrom, and the upper ends, arrested from further forward movement by the stops *m*, attached to the brackets *h*, as shown fully in Fig. 80 2 of the drawings, thus constituting an elevating and sustaining means for the cultivator.

The shoes E, which are pivotally connected to the arm *d* of the sleeves or hubs D, to secure motions equal to two quadrants, or thereabout, may be provided with diagonal braces, extending from the upper ends to the bases, to obtain additional strength.

85 We reserve the right to vary the construction, as well as the arrangement of the parts without departing from the spirit of the invention.

90 What we claim as our invention, and desire to secure by Letters Patent, is—

95 1. The combination, in a cultivator, of the arched axle A, of the couplings C, pivoted to the spindles of the axle, and provided with stops *c*, adapted to abut against the vertical portions of the axle, the plow-beams pivoted 100

to said couplings, and the sleeves D, fastened to the spindles of the axle, and serving to hold the couplings in place and as attachments for the shoes E, substantially as specified.

5 2. The combination, with the plow-beams and plows, of the fulcrum-plate h, its stop m, the pivoted shoe F, and the catch k, the whole arranged to operate substantially as specified.

In testimony whereof we affix our signatures in presence of two witnesses.

JOHN B. CHRISTIAN.
WILLIAM D. HANSON.
